Primary Examiner — Karen S Acker(74) Attorney, Agent, or Firm — Cort Flint; Monahan & Moses, LLC(57) CLAIM

The ornamental design for a american flag with three dimensional stars, as shown and described.

DESCRIPTION

FIG. 1 is a front elevation of my new american flag with three dimensional stars; and,

FIG. 2 is an enlargement of a corner of FIG. 1 showing my new design.

The broken lines in the drawing represent environmental subject matter that forms no part of the claimed design.
